(57) **CLAIM**

The ornamental design for a display screen with graphical user interface for a healthcare command center computing system, as shown and described.

DESCRIPTION

The FIGURE is a front view of a design for a display screen with graphical user interface for a healthcare command center computing system showing the new design.

The outermost rectangular broken line showing the display screen and all other broken lines showing portions of the graphical user interface are included for the purpose of illustrating portions of the article and environmental structure and form no part of the claimed design.

1 Claim, 1 Drawing Sheet
